UNITED STATES PATENT OFFICE.

GEORGE M. KOONTZ, OF VANATTA, OHIO.

FENCE-POST.

No. 830,599.

Specification of Letters Patent.

Patented Sept. 11, 1906.

Application filed March 30, 1906. Serial No. 308,967.

To all whom it may concern:

Be it known that I, GEORGE M. KOONTZ, a citizen of the United States, residing at Vanatta, in the county of Licking and State of Ohio, have invented certain new and useful Improvements in Fence-Posts; and I do hereby declare the following to be a full, clear, and exact description of the invention, such as will enable others skilled in the art to 10 which it appertains to make and use the same.

My invention relates to new and useful improvements in fence-post construction, and particularly to that class adapted to be 15 built up of wood, cement, and metal.

The object of my invention is to provide a cheap, durable, and easily-constructed device and one wherein the wire-securing members may be readily placed therein and 20 securely held in position.

A further object is to provide suitable means for holding the cement around the wooden portion of the post and at the same time lend strengthening qualities thereto.

25 Other objects and advantages will be more clearly set forth in the accompanying specification, and pointed out in the claims.

In the accompanying drawings I have shown the preferred form of my invention.

30 In said drawings, Figure 1 is a perspective view of my improved post, showing the same in position within the ground. Fig. 2 is a central longitudinal sectional view showing the metal portion thereof in full lines. Fig. 35 3 is an enlarged detail sectional view of the upper end of the post. Fig. 4 is a similar view showing the wire-securing devices in position, and Fig. 5 is a transverse sectional view as seen from the dotted line 5 5, Fig. 4.

40 Referring to the figures by numerals of reference, 1 indicates the core of my improved post, which is preferably made of a strip of wood or like material, around which is secured a metal frame 2, the free ends of 45 which are slightly spaced apart, as shown at 3, to provide an unobstructed access to the core 1 for the wire-securing devices. That part of the metal frame 2 directly opposite the opening 3 is provided with downwardly-

50 projecting tongues 4, said tongues being formed by striking out a portion of the surface of the metal frame and disposing a section of the struck-out portion parallel with the surface of the metal frame. The opposite sides of the metal frame are provided with similar struck-out portions 5, said por-

tions 5 being upwardly directed, as best shown in Figs. 2 and 3. The core 1 and metal frame 2 are entirely inclosed within a composition casing 6, said casing preferably 60 consisting of cement or other like material, said material being provided with a plurality of openings 7 adjacent the opening 3 in the metal frame into which are adapted to take nails or the like 8, said nails having suitable 65 heads 9 at their outer ends. Loosely mounted upon the nails 8 are wire-securing hooks 10, by which means the several strands of wire composing the fence are securely held in position and spaced apart.

70 In constructing my improved post the core 1 is first surrounded with the metal frame 2, as shown, and said parts then placed within a suitable mold, (not shown,) and the material composing the outer casing 6 disposed around said core and frame, after which said parts remain in said mold until the cement or the like is sufficiently hardened to retain its shape, and then the same is removed from 75 said mold. While the cement is still in its green state, the holes 7 are formed by inserting an instrument through said cement at predetermined intervals, thereby forming openings through which a nail 8 may be inserted. After the cement has become thor- 80 85oughly hardened, it is placed in proper position in the ground and the fence-wires 11 secured thereto.

85 In securing the wires 11 to the post said wires are first engaged with the hooks 10, 90 after which a nail is inserted through the enlarged head upon said hook and the free end thereof placed within the opening 7 in the cement, after which said nail may be driven into the core 1 sufficiently to direct the hook 95 10 against the cement casing of the post. It will be seen that by having the core 1 of wood or like material and the cement surrounding the same provided with holes 7, the nails can be readily driven into the core 100 and extracted without breaking or in any way injuring the cement casing. It will also be seen that by providing the metal frame 2 with the struck-out portions 4 and 5 the cement will be disposed upon opposite sides of 105 said struck-out portions, thereby strengthening the casing 6 and securely holding the same in position around the core and metal frame.

110 What I claim is—

1. A fence-post comprising a core, a metal frame surrounding said core and spaced

apart at its meeting ends to form an opening, oppositely-disposed tongues struck out of the metal frame, and a casing of cement surrounding said core and frame and engaging said tongues.

2.. A fence-post comprising a core of wood, a metal frame disposed around said core, the meeting edges thereof being spaced apart to form an opening, upwardly and downwardly projecting tongues integral with said frame, a casing entirely surrounding said frame and core and engaging said tongues, said casing having openings therein, nails adapted to be

inserted into said openings and driven into said core between the free ends of the frame, and a hook member carried by said nails adapted to engage wires and to hold them in place.

In testimony whereof I have signed my name to this specification in the presence of two subscribing witnesses.

GEORGE M. KOONTZ.
